CLAIM

The ornamental design for a clear sticky mat, as shown and described.

DESCRIPTION

FIG. 1 is a top plan view of a clear sticky mat in accordance with the present invention; in all figures, the internal lines are markings on the top surface of the clear sticky mat and represent the color white.

FIG. 2 is a closeup view of the circled area labelled 2 in FIG. 1.

FIG. 3 is a bottom plan view of the clear sticky mat of FIG. 1.

FIG. 4 is a right side elevation view of the clear sticky mat of FIG. 1, with the left side being a mirror image.

FIG. 5 is a front elevation view thereof of the clear sticky mat of FIG. 1, with the rear being a mirror image thereof.

FIG. 6 is a top perspective view of the clear sticky mat of FIG. 1.

FIG. 7 is a top plan view of a clear sticky mat in accordance with the present invention.

FIG. 8 is a closeup view of the circled area labelled 8 in FIG. 7.

FIG. 9 is a bottom plan view of the clear sticky mat of FIG. 7.

FIG. 10 is a right side elevation view of the clear sticky mat of FIG. 7, with the left side being a mirror image.

FIG. 11 is a front elevation view thereof of the clear sticky mat of FIG. 7, with the rear being a mirror image thereof; and,

FIG. 12 is a top perspective view of the clear sticky mat of FIG. 7.

The broken lines shown in the Figures depict environmental subject matter only and are not part of the claimed design.
